DISPENSER FOR VISCOUS MATERIAL

Harry M. Hosmer, Mill Valley, Calif.

Application November 26, 1948, Serial No. 62,056

3 Claims. (Cl. 222—80)

1

This invention relates to a dispenser for viscous material such as pastes, creams, ointments, and any other materials of similar physical characteristics.

One of the objects of the invention is the provision of a container and dispenser for viscous material that has sufficient rigidity to withstand accidental distortion, breakage, and yet which is compact, light in weight, and as easily carried as conventional distortable tubes such as are employed for tooth paste and other material.

Another object of the invention is the provision of a container and dispenser for viscous material that is adapted to be supported upright on one end, and from which the contents is readily and easily discharged by mere manual rotation of one part relative to the other.

A still further object of the invention is the provision of a container and dispenser for viscous material that is automatically shortened or decreased in size in direct proportion to the amount of material discharged therefrom, yet which container is relatively rigid and may stand upright on one end at any time and is not susceptible to accidental breakage or distortion.

An additional object of the invention is the provision of a compact, simple container and dispenser for viscous material that includes a closure having apertured piston means for forcing material from the container and at the same time paring away the container in direct proportion to the material discharged from said container until all of the material has been discharged from the container and substantially all that remains is the closure and bottom of said container.

An added object is the provision of a relatively rigid walled container and dispenser for viscous material that is simple to make, easy to use, and which container includes means for effecting a more complete exhaustion of material therefrom than in the case of conventional tubes such as those employed for tooth paste and in which the walls are distorted in order to effect a discharge of material.

Other objects and advantages will appear in the description and in the drawings.

In the drawings,

Fig. 1 is a side elevational view of the container and dispenser.

Fig. 2 is an enlarged vertical part sectional and part elevational view taken substantially along line 2—2 of Fig. 1.

Fig. 3 is a sectional view taken along line 3—3 of Fig. 2.

In detail, the main body of the dispenser, as illustrated, comprises a cylindrical container, generally designated 1, having a cylindrical wall 2 and an end wall 3. The end of the container opposite the end wall 3 is open, and axially facing side of end wall 3 that is directed toward the

2

open end is preferably convexly curved as shown in Fig. 2.

The cylindrical wall of the container is externally threaded to provide a helical groove 4 extending from the open end of the container to the closed end. This groove functions to form a helical line of weakness as well as a guide for a cutter and a thread on a closure, generally designated 6, which closure is constructed as follows:

Closure 6 comprises a central piston portion 7 that includes a top wall 8 opposed to bottom wall 3 and having curved concavely on the side facing the bottom wall to correspond with the convex curve of the latter. This top wall is formed with a central externally threaded and centrally apertured boss 9 that projects in a direction axially outwardly of the container. A conventional internally threaded cap 10 is adapted to be secured by its thread on boss 9.

Said piston portion 7 has a cylindrical peripheral surface 11 that is adapted to relatively closely fit within the container for rotary and linear movement of said portion relative to the axis of said container.

Concentric with piston portion 7 and spaced outwardly thereof is an annular flange 12, which flange is integrally secured to the portion 7 by annular web 13 that extends across the outer edge of the container. It will be seen from the foregoing that the axially extending portion 7, flange 12 and web 13 virtually form the walls of an annular recess into which the outer end of the container extends.

The axially inwardly facing side of flange 12 is formed with an outwardly projecting thread 14 that is adapted to fit into and to follow groove 4 of the external thread on the container.

At the end of thread 14 that is adjacent the web 13 is a cutting blade 15 that extends transversely across the space between portion 7 and flange 12, which blade has its cutting edge 16 facing in the direction of arrow 17 (Fig. 3) which is the normal direction of rotation of the closure 45 for screwing it onto the container.

Flange 12 is formed with a laterally directed discharge opening 18 extending from the trailing edge of blade 15, and a wall 19 extending across the space 20 (Fig. 3) between flange 12 and portion 7 is provided just above the level of the blade 15.

Upon rotation of the closure in direction of arrow 17, the cutting edge of blade 15 will immediately commence paring off a strip-like portion of the container walls equal in axial thickness (relative to axis of container 1) to the space between adjacent turns of groove 4, and the cutting action will be along the bottom of groove 4 where the container walls are of minimum thickness.

The strip-like portion progressively pared from

the container wall will pass out of the opening 18 in generally the direction of arrow 21 (Fig. 3).

Simultaneously with the paring off of the container wall, the piston portion of the closure will move toward closed end 3, and the viscous material of whatever kind that may be in container 1 will be forced out of the central aperture 23 in boss 9, it being assumed that cap 10 has first been removed.

The amount of material discharged from within the container is in exact proportion to the advance of the closure along the container and to the amount of the container that is pared away. When the closure reaches the bottom 3, all of the material between the closure and the bottom will be discharged into aperture 23, and the amount of material that may be left in the aperture is directly proportional to the length of the same and its diameter. Obviously the boss 9 may be relatively short, and in such a case the cap 10 may be made sufficiently long to enable easy grasping by the fingers of the hand. If desired, the boss may be so short that the closed end of the cap is practically coplanar with the web 13.

While the cylindrical walls 2 may have an internal helical groove formed therein and portion 7 may be externally threaded to fit said groove, the present structure is preferable since a smooth inner surface on the container and a smooth outer surface on portion 7 insures a better fit with no likelihood of objectionable leakage if properly fitted.

The material of the container may be a plastic composition having easy cutting characteristics. The parings are, of course, easily broken away after they pass through the opening 18. Any other desired material may be used or any suitable combination of different materials. The cutter, of course, is preferably of steel. Its cutting life only extends to the cutting of one container, hence it need not be of any very costly material. This cutter, in which the closure is molded, may be molded into place or it may be inserted later on in any one of many suitable ways.

As is seen in the drawings, the container is adapted to be stood on end without lateral support, and the body is preferably sufficiently rigid to withstand accidental distortion and breakage. This rigidity enables the same to be readily held in a suitable wall clamp or bracket.

The pitch of the threads may be varied to adapt the container to relatively heavy viscous material that would be difficult to easily dispense unless a relatively low degree of pitch is used.

It is also obvious that the closed end of the container could be apertured for discharge of material upon moving the closure carrying the cutter toward it.

While the cutter could be inclined so as to cut its way toward the opposite end of the container irrespective of threads, or a groove in the container, the use of the groove is preferable since it greatly facilitates the cutting and insures a uniform cut being made.

I claim:

1. A dispenser for viscous material comprising a tubular container closed at one end and an apertured closure at the opposite end in threaded engagement with said container for movement toward said closed end upon rotation of said closure in one direction relative to said container whereby said material will be forced out of said aperture, a cutter on said closure in engagement with said container for progressively cutting away

the end of said container at said closure upon said rotation to permit said movement of said closure, the said closed end of said container comprising an end wall formed with a convexly curved inner surface facing toward said closure and the side of said closure facing said end wall being concavely curved complementary to the said curve of the surface of said end wall to facilitate substantially complete discharge of said material from said container when said closure is moved to said closed end.

15 2. A dispenser for viscous material comprising an externally cylindrical container open at one end and closed at the opposite end and having a continuous thread formed on its cylindrical outer side extending from said open end to substantially said closed end, a closure for said open end having a flange projecting axially of said container over the outer side of the latter formed with an internal thread adapted to engage the thread on said container for movement of said closure toward said closed end upon rotation of said closure in one direction relative to said container, a cutter secured to said closure and extending transversely across the edge of said container at said open end and at a point spaced from the free edges of said flange for progressively cutting away said container as said closure is rotated to move toward said closed end, said closure being formed with a discharge opening for discharge of material from within said container under pressure created as said closure is moved toward said closed end, and an opening formed in said flange adjacent said cutter for discharge of the part of said container that is cut away by said cutter.

30 3. A dispenser for viscous material comprising a cylindrical tubular container open at one end and closed at the opposite end, the walls of which are externally threaded from said open end to substantially said closed end, a closure for said open end having a central piston portion projecting into said container and in relatively close fitting relationship to the inner surface of said container, a discharge aperture formed in said portion adapted to discharge material within said container upon movement of said portion toward said closed end, a flange carried by said closure extending over the outer sides of said container at said closed end and internally threaded for engagement with the external threads on said container whereby said closure will move toward said closed end upon rotation of said closure in one direction relative to said container, a cutter 35 secured to said closure extending transversely across the edge of said container having a cutting edge directed generally circumferentially of said edge of the container for progressively cutting away said container from its open end upon said rotation of said closure, and an opening formed in said closure for discharge of the material of said container so cut away.
